UNITED STATES PATENT OFFICE

THOMAS LORD AND HAROLD J. BRUNK, OF CHICAGO, ILLINOIS, ASSIGNEES, BY MESNE ASSIGNMENTS, TO C. F. PEASE COMPANY, A CORPORATION OF DELAWARE

CONTINUOUS WASHING AND DRYING MACHINE FOR BLUE PRINTS AND THE LIKE

Application filed May 26, 1928. Serial No. 280,862.

Our invention relates to improvements in so called continuous machines for washing, developing, drying and rolling up of blue prints, blue line prints, negatives and other photographic prints.

In such machines as have been used commercially heretofore, the wind up device at the rear of the machine pulls the paper through the entire machine with the exception 10 of the printer. This maintains the paper under considerable stress, causing wrinkles in it and a great amount of distortion. To avoid wrinkles, it has been customary heretofore to arrange bent tubes transversely of 15 the span of paper to cause a bulge in the paper. However, this puts more stress on the paper and while it decreases the wrinkles at that particular location, the additional stress causes more wrinkles elsewhere. 20 Wrinkles are also caused by the fact that the sheet of paper widens materially as soon as it has become wet, resulting in a tendency to hang in folds.

Also, in the application of potash or hypo, 25 after the first water wash has been applied, the method which has given the most success in the past has been to use metal scrapers in contact with the surface of the paper, the one on the bottom serving to scrape the first water 30 wash from the paper so that the water on the surface and the potash and hypo sprayed onto the paper do not mix. The other scraper is intended to prevent the final wash from mixing with the potash or hypo.

35 These scraper edges sometimes injure the surface of the paper partly due to the fact that the paper at that stage is very wet and semiplastic. Also, said scrapers are not entirely effective, as wrinkles in the paper passing over said scrapers permit a leakage of water or potash at that point.

One object of the invention is to provide an improved machine of this character in which 40 wrinkling of the paper is eliminated, in which the surface of the paper is not damaged by scrapers, and in which there is a complete separation of the water washes from the hypo or potash.

Another difficulty which has arisen heretofore is that the open type of drying has been

employed. That is, the paper has been merely looped around a frame with a source of heat between the spans, the paper travelling through the air without any support. Any draft of air in the room under these conditions affects the heated air which accomplishes the drying. Furthermore, it has been difficult to maintain the heated air at a uniform temperature. 55

Another object of our invention is directed to the drying of the paper by passing it over heated rollers, the temperature of which may be accurately regulated and which have the advantage of smoothing out or ironing the paper and other advantages as well. 60

As contributory to the general objects previously presented, we have as further objects to provide a continuous washing and drying machine having a tension roll arrangement to take up slack in the paper; one having nozzles for applying the water to the paper in the form of a mist as it travels downwardly at a certain predetermined angle whereby rapid expansion of the paper does not injuriously affect the finished product; 65 one having a flat plate glass backing adjacent the water spray to deaden the noise; one having various rolls for smoothing out wrinkles and removing the liquid from the paper; one having a potash or hypo tank with 70 automatic means for controlling the supply; one having means at the end for maintaining an adjustable tension on the paper in drawing it through the machine and one having a device for rolling up the finished print tightly on a roll which is readily detachable from the machine. 75

In the drawings:

Fig. 1 is a side elevation of the machine, the hand operating means being omitted for the purpose of clearness. 80

Fig. 2 is an enlarged view of a portion of the device showing the parts more in detail than is shown in Fig. 1. 85

Fig. 3 is an enlarged fragmentary elevation showing certain of the roller construction and operating mechanism. 90

Fig. 4 is an enlarged sectional elevation of the potash or hypo applying mechanism; and 100

Fig. 5 is a sectional elevation taken on line 5—5 of Fig. 4.

The blue printing machine has a driven roller 1 mounted thereon over which the paper 2 passes to the washing and drying machine. The paper is in the form of a continuous sheet and is usually several feet wide. It passes under a drag roller 3, the latter being secured to a pair of chains 4 passing around pairs of upper and lower sprockets 5, the upper sprockets being secured to the shaft 6 to turn together. An adjustable counter excess weight 7 is also carried by said chains to balance the weight of the roller 3 which maintains the proper tension on the paper 2.

The function of said roller is to furnish enough weight in the loop of the paper to keep any slack from developing during the progress of the paper through the washer and drier. Such slack would develop from a slight difference in speed between the printer and washer and also from the elongation of the paper due to its expansion while it is wet. In operation, the drag roller 3 moves up and down slightly as conditions may demand.

From roller 3, the paper passes over roller 8 and down at an angle of about thirty degrees over a piece of flat plate glass 9. The glass constitutes a noiseless backing for the paper while it is being subjected to the washing action of high speed water sprays 10. The nozzles from which the water issues are described more fully in the pending application of Harold J. Brunk, Serial No. 255,482, filed February 18, 1928, Patent No. 1,812,470, granted June 30, 1931.

The paper next passes over roller 11, above which is located a back water wash 12 which directs water against the rear surface of the paper. The angle of the glass and the angle assumed by the paper between rolls 8 and 11 is important, for the reason that as soon as the paper is wet it widens very materially. For example, in the case of thin paper 42 inches wide when dry, the width increases approximately 2 inches almost immediately after it passes the water sprays. If the paper in passing over roller 8 hung down in a vertical position rather than at a substantial angle such as shown, the paper would wrinkle. With the arrangement shown, however, the paper in passing over the roller 11 is smoothed out and prevented from wrinkling, after which it passes down, substantially vertically, over the roller 13 and also is deflected slightly at said roller in passing to the roller beneath. Any slight waves in the paper approaching wrinkles are thus smoothed out over the roller 13, which exerts pressure against said paper.

The back water wash 14 is also applied directly above said roller to insure a condition of equal expansion and to prevent curling

of the paper at the edges, such as would result if the paper were wet on one side only, the same being true with reference to the back water wash 12.

The roller 15 at the bottom of the machine is preferably made of brass and is of fairly large diameter and is driven at initial speed through helical gears 16 from a shaft 17. This roller, because of its large size, has an ironing effect upon the paper and it also serves to pull the paper on through the machine, overcoming the friction and more particularly the necessary drag that is exerted by the roll 3.

The paper next passes over rollers 18 and 19 which project slightly up into the line of travel. These rolls support the weight of the paper and also prevent wrinkles by the slight ironing action which they effect where they engage the back surface of the paper. They also have the effect of wiping or wringing the surplus water from the back of the paper. The surplus water is completely removed from the front surface of the paper by the next roll 20, which is an idler roll. A tray 21 is located beneath the rolls 15 to 20 inclusive to collect the surplus water. The paper passes from the roll 20 over the roll 22 which is a potash or hypo deposit roll for developing purposes. This roll is driven in the direction of travel of the paper, but has a surface speed much faster than that of the paper, preferably twice as fast. Said roll is rubber covered and dips into the potash tray 23, the liquid being supplied from the potash or hypo tank 24. Two such tanks may be provided as shown in Fig. 1, although one tank or the other will suffice if the machine is to be used entirely for developing blue prints on the one hand, or negatives of the black line or brown line type on the other hand.

The level of the liquid in the tray 23 is maintained by one of the constant level floats 25^a each of which is positioned in partitioned off chamber 25 near one end of the respective tank 24, the liquid flowing to the tray 23 through one of the pipes 25^b, so that as the potash or hypo is used, the level in the tray remains constant. The details of such arrangement being well understood, they are not described herein in greater detail.

The reason the roll 22 is rotated at a peripheral speed faster than that of the paper, is to cause a puddle of liquid to be maintained between the roll and the paper as shown at 26. This puddle is sufficient to insure uniform application of the potash or hypo to the surface of the paper. The angle of the paper as it passes over the rolls 20 and 22 is important for the reason that if the angle were too great by having the roll 20 an inch or two lower than that shown, the potash or hypo in the puddle would flow back down the paper onto the roll 20, causing streaks in the paper. In passing over the roll 22, the paper is held

firmly in contact with the same, thus preventing any of the liquid from the puddle from passing over and onto the next roll 27 under which the paper passes. The arrangement 5 described insures great economy in the use of the potash or hypo and furthermore there is substantially no surplus of either to be washed off afterwards.

The rolls, 22 and 27 are driven by a chain 10 28, the roll 27 being driven at paper speed, delivering the paper upwardly past a second water wash 29. A tray 30 catches the water from said water wash which is slightly mixed with potash and liable to spot if allowed to 15 fall onto the paper below, and has a drain outlet 30^a in one end. The downward slope of the paper between the rolls 22 and 27 is important, the arrangement being such as to prevent any water from getting around and 20 into the potash or hypo trough 23. This particular arrangement insures that no water on the surface of the paper from the first water wash or from the last water wash will ever mix with the hypo or potash in the trough 23, 25 and the parts described in the drawings require no adjustment.

The roll 27 is, however, carried by movable brackets 31, mounted on a pivot 32, whereby said roll may be released when the machine 30 is stopped for any length of time, by swinging it upwardly, as by means of a handle 31^a, as shown in Fig. 4. This releases the tension on the paper and prevents it from sticking to the roll 22, and also prevents it from breaking 35 due to contraction during the process of drying. The water spray 29, lubricates the roll 27, and prevents the roll sticking to the paper as well as keeping the roll and the back of the paper clean.

40 After leaving the roll 27, the paper passes upward through a water spray 33, very similar to the one previously referred to, thereby completely washing the surface of the paper and removing any trace of potash or hypo.

45 The paper then passes over rolls 34 and 35 and under the glass scraper 36, the latter having a smooth and rounded edge and being carried on adjustable arms 37. In addition to scraping the paper surface free of any surplus water, said rounded edge has a smoothing action, ironing out any slight wrinkles which may appear.

Above the rolls just named, the paper 50 travels past a rod 38, carried by an adjustable arm 38^a which passes the paper in the direction of the copper drying drum 39. Said rod 38 is used primarily wherever thin negative paper is being run. Its action is such as to guide the paper in a straight line parallel 55 with the drum axis. Said drying drum may be heated either with gas or electricity, or in any other suitable manner, the back or unprinted side of the paper being in contact with said drum. In Fig. 1, the gas burners 60 65 39^a are shown for the purpose of illustration.

The paper then passes over idler rollers 40, and around a second drying drum 39' which is a duplicate of the drum 39. Said drums are driven from a vertical shaft 40', a chain 40^a connecting the two.

Even though the paper, in passing the rod 38 and onto the first drum 39, should contain numerous wrinkles, said wrinkles would completely disappear by the time the paper has left the first heating drum, such elimination of the wrinkles being based to a great extent on the relation of the rolls 40 to each other, and to the heating drums. By providing two separate heating drums instead of one drum, a closer degree of heat can be maintained. 70 For example, the paper passes over the first heating drum with just a slight amount of heat applied thereto partially drying the same, and by permitting it to pass over the rollers 40, after covering the short span from the first heating drum to the first roller 40, it is given an opportunity to contract before it makes contact with the second heating drum. With this arrangement the machine 75 can be run at high speed which otherwise 80 would not be possible.

From the heating rollers, the paper passes over idler roll 41, which may be slightly heated by a burner 41^a, between the same and a spring pressed ironing shoe 42, the latter 85 making light spring contact with said roll. This puts a final finish on the paper and in the case of thin negatives serves as a heating roll where no heat is supplied to the drums 39. It will be noted that the back of the paper 90 is in contact with both of said drums as well as with said final heating roller.

The paper then passes over the roller 43 which is driven from the vertical shaft 40' through helical gears 44, 44'. Elastic tapes 45 pass around rollers 46, 47, the latter being an idler roll mounted on the swinging arm 48, which is adjusted by a tension spring 49. Said helical gear 44 idle upon the shaft and drives the roll 43 through a clutch hub at the hand wheel 50, which is keyed to the shaft. The object of this arrangement is to permit a leader to be pulled through the machine by pulling out the hand wheel thus disengaging 100 the clutch and allowing roll 43 and also 46, which is driven from 43 by spur gears 51, to be operated by the hand wheel. Said rolls 43 and 46 are driven slightly faster than the normal speed of the paper, thereby exerting a pulling action at all times on the paper and holding it firmly in contact with the surface of the drying drums. This pulling action can be gauged to a very fine point, and any pull required can be obtained by adjustment 105 of the spring 49, which may be provided with an adjusting nut 49^a. The action of roll 43 and the elastic tapes, is to slip slightly upon the surface of the paper, depending on the tension of the spring 49. Without this arrangement it would be impossible to have the 110 115 120 125 130

sheet delivered smooth and flat from the heating drums without the use of belts to hold the paper against the second one of said heating drums.

5 As a final step the paper is wound on wind-up roll 52 which is a detachable roll carried upon the spring pins 53, 54. Said roll is driven by pulley 55, the connection being by a raw hide belt 54^a which has a tendency to slip as the roll of paper increases in diameter. Said roll is quickly detached by pulling toward the right which moves the spring 54 and permits the cross pin 56 to be released from the slot 57 in the end of said roll.

15 What we claim is:

1. A washing and drying machine comprising side frames, rolls supported therein, means for drawing the paper through said machine, one of said rolls being intermediate 20 said other rolls and serving to apply potash or hypo to the paper passing over the same, means for driving said roll at a surface speed faster than the movement of said paper, the rolls at opposite sides thereof being positioned at elevations lower than said applying roll whereby the paper ascends to and descends from said applying roll so as to insure a puddle between the approaching span of paper and the periphery of said roll.

25 2. In a washing and drying machine, a series of rolls, means for positively driving two of said rolls at different rates of rotation, a trough in which the faster of said rolls dips to apply potash or hypo to washed paper passing over the top thereof, a third roll over which said paper passes in travelling from the slower of said driven rolls to the other and so located that the span of paper approaches said second mentioned roll at a slight 30 incline above a horizontal position, and a tray beneath said rolls to collect the water removed from said paper by said slower driven roll and by said third roll.

3. In a washing and drying machine, a 45 group of three rolls, means for driving the middle roll in the direction of movement of the paper over the same, a liquid tray into which said middle roll dips, said rolls being so arranged that the paper passes over the 50 first two rolls in a direction inclined slightly upwardly whereby said middle roll maintains a puddle of liquid on the lower surface of said paper adjacent said roll then passes downwardly at a substantial angle beneath 55 said third roll, a water tray beneath said third roll and a back water wash for the paper located just beyond said third roll.

4. In a washing and drying machine for light sensitive material comprising a roll for 60 applying potash or hypo to said material, said roll being rotatable at a surface speed greater than the travel of paper over the same and in the same direction, a tray beneath the same, a supply tank communicating with said tray and means for automati-

cally maintaining the level of the liquid in said tray.

5. In a washing and drying machine, a roll for applying potash or hypo to the paper, a tray beneath the same, a plurality of tanks communicating therewith each tank having a reservoir and an auxiliary chamber and means in each tank controlled by the level of the liquid in said auxiliary chamber for automatically controlling the admission of liquid from said reservoir whereby said tray may be supplied with liquid from any one of said tanks and the level thereof maintained constant.

6. Apparatus of the class described comprising a liquid applying roll, a trough for such liquid into which said roll dips, means for moving paper over said roll independently of the rotary movement thereof and means for rotating said roll in the direction of movement of the paper over the same and at a surface speed greater than the movement of said paper.

7. Apparatus of the class described comprising a paper driving roll, a liquid applying roll over which said paper passes, means for rotating said roll in the direction of movement of said paper and at a surface speed higher than the movement of said paper, and means in front of said applying roll for guiding the paper to said roll at such incline as to assure the maintenance of a puddle of liquid between the approaching span of paper and the periphery of said roll.

8. Apparatus of the class described comprising a supporting frame, a roll supported therein, a tray into which said roll dips for applying liquid from the same to paper passing over said roll, means for rotating said roll in the direction of movement of said paper and at a surface speed higher than the speed of travel of said paper, a second roll at the front of said driven roll positioned at a lower elevation for guiding the paper to said first roll at an incline whereby a puddle of liquid is maintained against the lower surface of said paper adjacent the periphery of said first roll, and a third roll at the rear of said first roll and having its under surface at a lower elevation than the top of said first roll and coacting with said second roll to hold the paper in firm contact with said first roll to prevent the passage of excess liquid from said puddle, beyond said first roll.

In testimony whereof we have subscribed 120 our names.

THOMAS LORD.
HAROLD J. BRUNK.
